UNITED STATES PATENT OFFICE.

WILLARD S. FREEMAN, OF ST. CLOUD, MINNESOTA.

ALARM FOR INCUBATORS.

No. 810,931.

Specification of Letters Patent.

Patented Jan. 30, 1906.

Application filed May 6, 1905. Serial No. 259,224.

To all whom it may concern:

Be it known that I, WILLARD S. FREEMAN, a citizen of the United States, residing at St. Cloud, in the county of Stearns and State of Minnesota, have invented certain new and useful Improvements in Alarms for Incubators, of which the following is a specification.

My invention relates to electric-actuated alarms for use in combination with incubators to indicate when the temperature thereof gets too hot or too cold, showing that the apparatus is not working properly, and has for its object the provision of a circuit-closing apparatus to be used in connection with the damper-regulating arm usually employed in connection with the thermostat and so constructed and arranged that the weight on the end of the damper-regulating arm comes in contact with the contact-plates and closes the circuit between a battery or other source of electric energy and a bell or other desired alarm.

The construction and advantages of my invention will be explained in detail herein-after and illustrated in the accompanying drawings, in which—

Figure 1 is a view showing the top of an incubator, a damper-regulating arm, and my improved circuit-closer in position; and Fig. 2, an end view of the damper-regulating arm and my circuit-closer in position.

In the drawings similar reference characters indicate corresponding parts throughout the several views.

A represents the top of an incubator-casing; B, the damper-adjusting lever fulcrumed thereon, having a weight C on one end, and a rod D secured to said lever and to any suitable construction of thermostat inside of the incubator.

As sometimes the heat-regulating means fail to operate or the lamp that is used to supply the heat burns out or is extinguished, I have provided an alarm to warn the operator when the temperature is either too hot or too cold to properly operate the incubator. My alarm consists of an electrically-actuated bell or other signal E having electrical connection with a suitable battery F; and the invention consists of a circuit-closing device, mounted on the top of the incubator A and consisting of an insulated base G, two slotted metal uprights H, secured to said base G, and metal contact-pieces I, secured in said slotted uprights H by means of screw-bolts J. Said bolts J have mounted thereon two nuts, one

of said nuts (designated K) serving to hold the bolt in position on the slotted upright H, while the other nut L, which may be a wing-nut or other hand-operated structure, serves to hold the contact-plate in place, each contact-plate being made L-shaped, with the shorter portion i perforated to receive the bolt J, while the longer portion is made tapered, as shown at i'. Two contact-plates I are secured to each upright H directly opposite one another and the base G so positioned that the weight C is between the plates I, and when the arm B swings approaches or contacts with two of said plates. The wire M from the positive pole of the battery F is secured to one upright H, while the wire N is secured to the other upright H and is connected with the alarm E.

O represents the conductor from the bell back to the battery F.

It will be understood from the above description and an inspection of the drawings that when the heating apparatus and regulating means operates properly the weight C does not contact with any of the plates I, but that should anything happen to the heating apparatus, so that the temperature gets either too hot or too cold, the weight C contacts with the two plates near the base or top of uprights H, thus closing the circuit between the battery F and alarm E, which will warn the operator of the condition, so that it may be attended to. It will be understood that by properly positioning the plates I the apparatus may be arranged to give warning at any predetermined degree of heat or cold and that, if desired, the uprights H may be marked, so that the plates may be positioned with approximate exactness.

Having thus described my invention, what I claim is—

1. A temperature-indicating alarm comprising the combination of an incubator, a thermostat contained therein, a damper-operating lever fulcrumed on said incubator, a balance-weight on one arm of said lever, a rod connecting said lever with the thermostat, a circuit-closing device secured to said incubator consisting of two slotted uprights positioned on opposite sides of said balance-weight, angular contact-plates secured in said slots above and below said weight and adjustable on said uprights, the extended portions of said plates being tapered, an alarm-signal, and a normally open circuit connecting said uprights and alarm, said

weight being adapted to move between the contact-plates and close the circuit to said alarm by contacting with them, substantially as shown and described.

5 2. A temperature-indicating alarm comprising in combination with an incubator, a thermostat contained therein, a damper-operating lever fulcrumed on said incubator, a balance-weight on one arm of said lever, and
10 a rod connecting said lever with the thermostat, a circuit-closing device secured to said incubator consisting of two slotted uprights positioned on opposite sides of said balance-weight, L-shaped contact-plates secured to
15 the uprights through the slots therein above

and below said weight by means of set-screws, the extended portion of said plates being tapered, an alarm-signal, and a normally open circuit connecting said uprights and alarm, said weight being adapted to move between 20 the contact-plates and close the circuit to said alarm by contacting therewith, substantially as shown and described.

In testimony whereof I hereunto affix my signature in the presence of two witnesses.

WILLARD S. FREEMAN.
